PRECISION VOLTAGE REGULATOR

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

In the field of electronics, a need exists for a device which will provide a precision reference voltage but does not itself require a regulated voltage supply. Most prior devices which provided a precision reference voltage require a voltage supply having at least good regulation.

SUMMARY OF THE INVENTION

The present invention is a precision voltage regulator having at least an operational amplifier and a plurality of constant resistive means and variable resistive means. In the preferred embodiment the constant resistive means are resistors, and the variable resistive means are zener diodes. The output of the operational amplifier is coupled to both its negative and positive inputs such that the voltage appearing across the terminal of one of the temperature compensated zener diodes is stable with respect to time, temperature, and load. Additionally, the input bias current and input offset current changes of the operational amplifier are much less critical in the present invention than in prior devices.

BRIEF DESCRIPTION OF THE DRAWINGS

FIG. 1 is a schematic diagram of a preferred embodiment of the invention which provides a positive reference voltage; and

FIG. 2 is a schematic diagram of a preferred embodiment of the invention which provides a negative reference voltage.

DESCRIPTION OF THE PREFERRED EMBODIMENT

Referring to FIG. 1 wherein the preferred embodiment of the present invention for generating a positive precision reference voltage comprises a supply voltage 10, an operational amplifier 12, zener diodes 16 and 26, resistors 20 and 24, and reference voltage output 28. The output of operational amplifier 12 is coupled to the diode 16 of diode 16-resistor 24 voltage divider, the junction of which is coupled to the negative input 18, the inverting terminal, of amplifier 12. The side of resistor 24 opposite the junction is coupled to ground. The amplifier output is also coupled to resistor 20 of resistor 20-diode 26 voltage divider, the junction of which is coupled to the positive input 22, the noninverting terminal, of amplifier 12. The anode end of diode 26 is coupled to ground. The circuit provides a highly regulated voltage across zener diode 26 at output 28.

The operation of the positive voltage-generating circuit is as follows: The purpose of the circuit is to retain the current 55 through diode 26 at a constant value, thereby producing a constant precision reference voltage at output 28. Since the input impedance of the high gain, differential, DC operational amplifier 12 is quite high, and therefore, draws approximately zero current, the current through diode 26 can be measured by the voltage drop across resistor 20. Similarly, the current passing through diode 16 can be measured by the voltage drop across resistor 24. If circumstances occur which cause the current through diode 26 to become smaller, that reduced current will be reflected by a reduction in the voltage at junction 14. The voltage at positive input 22 will change very little.

A decrease in the voltage at junction 14 results in an almost equal decrease in the voltage at negative input 18 since diode 16 tends to maintain a near constant voltage drop between junction 14 and terminal 18. Therefore, the voltage change at inverting terminal 18 will be much greater than the voltage change at noninverting terminal 22. As a result, the voltage at junction 14 will be driven in a positive direction; thereby, causing the current through diode 26 to increase, restoring it to its original value.

The sensitivity of the precision reference voltage appearing at output 28 to the various components of the circuit is as follows:

5

$$\frac{\partial E_1}{\partial V_1} = 1 + \frac{R_1 R_2}{R_3 R_4} \approx 1$$

$$\frac{\partial E_1}{\partial V_2} = \frac{R_1}{R_3}$$

$$\frac{\partial E_1}{\partial R_3} = -\frac{1}{R_3^2} \left[\frac{V_1 R_1 R_2}{R_4} + V_2 \right]$$

$$\frac{\partial E_1}{\partial R_4} = -\frac{1}{R_4^2} \left[\frac{V_1 R_1 R_2}{R_3} \right]$$

10

where:
 E_1 = voltage at output 28
 V_1 = voltage at noninverting terminal 22
 V_2 = voltage across diode 16
 R_1 = resistance of zener diode 26
 R_2 = resistance of zener diode 16
 R_3 = resistance of resistor 20
 R_4 = resistance of resistor 24

While applicant does not wish to be limited to any particular set of circuit constants, the following constants have proven to be useful in generating a positive reference voltage.

25

Symbol	Description	Value
V_1	Voltage at noninverting terminal 22	6.2 volts
V_2	Voltage across diode 16	6.2 volts
R_1	Dynamic resistance of diode 26	10 ohms
R_2	Dynamic resistance of diode 16	10 ohms
R_3	Resistance of resistor 20	800 ohms
R_4	Resistance of resistor 24	800 ohms

30

Referring to FIG. 2 wherein the preferred embodiment of the present invention for providing a negative reference voltage comprises a supply voltage 10, an operational amplifier 12, zener diodes 16 and 26, resistors 20 and 24, and reference voltage output 28. The operation of the negative voltage generating circuit is similar to that described above, and therefore, will not be repeated. The circuit of FIG. 2 is the circuit of FIG. 1 modified to provide a negative reference voltage.

While applicant does not wish to be limited to any particular set of circuit constants, the following constants has proven to be useful for providing a negative reference voltage.

Symbol	Component	Type or Value
10	Supply voltage	15-40 volts
12	Operational amplifier	LM 101
16	Zener diode	IN829A
20	Resistor	820 ohm, 3 watt
24	Resistor	820 ohm, 3 watt
26	Zener diode	IN829A
28	Reference voltage output	6.2 volts

Although standard zener diodes may be used in the present invention, improved results can be obtained by using temperature compensated zener diodes as diodes 16 and 26.

Note that reference voltage output 28 is insensitive to supply voltage 10, thereby, eliminating the necessity of providing a well regulated supply voltage to the present invention. Therefore, any supply voltage which provides an output within a large range of possible values may be utilized in the present invention.

What is claimed is:

1. A voltage regulator providing a precision reference voltage output, comprising:
 an operational amplifier providing an output;
 a supply voltage coupled to said operational amplifier; and

75

a plurality of variable resistive means for providing variable electrical resistance, and a plurality of constant resistive means for providing constant electrical resistance, coupled to said operational amplifier such that said variable resistive means and said constant resistive means are arranged in a plurality of voltage divider networks; wherein the voltage across at least one of said variable resistive means is a precision reference voltage.

2. The regulator of claim 1, wherein a first variable resistive means is coupled between the output and a first input of said operational amplifier, and a first constant resistive means is coupled between the output and a second input of said operational amplifier.

3. The regulator of claim 2, wherein a second variable resistive means and a second constant resistive means are coupled in combination between said first input and said second input of said operational amplifier.

4. The regulator of claim 3, wherein said first input is the in-

verting terminal of said amplifier, and said second input is the noninverting terminal of said amplifier.

5. The regulator of claim 4, wherein said first variable resistive means and said second variable resistive means are zener diodes, and said first constant resistive means and said second constant resistive means are resistors.

10 6. The regulator of claim 5 wherein the resistor end of said combination of said variable and said constant resistive means is coupled to the inverting terminal of said operational amplifier, and the diode end of said combination is coupled to the noninverting terminal of said operational amplifier.

7. The regulator of claim 6 wherein said zener diodes are temperature compensated zener diodes.

15 8. The regulator of claim 7 wherein the voltage across said second variable resistive means is said precision reference voltage output.
